RADIO STEERING CONTROL

Theophile E. Brockstedt, San Francisco, Calif.,
assignor to Washington Institute of Technology, Inc., a corporation of Delaware

Application August 28, 1930, Serial No. 478,498
Renewed April 17, 1935

20 Claims. (Cl. 172—282)

This invention relates to signal apparatus designed to accomplish the automatic steering of marine vessels and airplanes by radio control and this specification is in part a continuation of an application entitled Radio signal apparatus and methods, Serial No. 151,915, Filed: Dec. 1, 1926, Patent No. 1,865,826.

An object of the invention is to provide an instrument arranged for operation with the double modulation type directive radio beacon, described in the above identified patent and also described in another copending application, Serial 478,497, entitled Method of, and apparatus for, radio-dynamic steering control, of even date with this application, and in which instrument a plurality of mechanically tuned elements equipped with improved air vanes are arranged to make a positive non-vibrating electrical contact for the control of steering mechanism under particular operating conditions of the above mentioned instrument, the said instrument being also provided with means for indicating its operating characteristics under various conditions to assure facility and convenience in use.

Another object of the invention is to provide a selective relay arranged to make a non-vibrating electrical contact by means of vibrating reeds.

A still further object of the invention is to provide an air vane adapted for use on vibrating elements to develop unbalanced dynamic forces, and to further provide a movably supported member having an axis of rotation, and to which member the dynamic forces developed by the air vanes, and the centrifugal forces developed by the elements in vibration, are applied to produce a useful torque around the axis of rotation of said member.

Another object of the invention is to describe methods for translating constrained mechanical vibrations into continuous and also differential torques of constant and also variable magnitudes which may be employed for actuating various types of instruments and apparatus.

Other objects of the invention will be made apparent in the course of description.

A problem in the prior art has been the vibrating contact made by a vibrating reed.

I have devised means to eliminate the vibrating contact and yet retain the selective advantages of a vibrating reed as shown in Figs. 3 and 5.

In the use of vibrating reeds for special purposes, some damping may be required, and this is readily accomplished by the use of common forms of air vanes fixed on the free ends of the

reeds. In operation these reeds with their air dampers are wasteful of energy in two respects. The centrifugal force developed by the reed in vibration is lost and the resistance of the air overcome by the movement of the damper vane is energy consumed and lost. In Figs. 3, 4, and 5 I illustrate a method of producing and utilizing this otherwise wasted energy for useful purposes.

Fig. 1 in the drawing is a representation of a radio receiving device.

Fig. 2 illustrates the characteristics of the signals and the spatial arrangement of the zones of maximum amplitude of the directional signals, and also the zones of equal signal intensity of a double modulation directive radio range beacon.

Fig. 3 is a side view of a selective non-vibrating contact relay.

Fig. 4 is an illustration of the dynamic forces developed by a reed in vibration when having differently shaped air vanes attached at its free end and also showing how these forces are combined and applied to a cantilever to produce a useful torque at its axis of rotation.

Fig. 5 is a projection of a selective differential relay embodying some of the features of this invention in an instrument for automatically controlling the steering mechanism of vessels in accordance with the signals received from a particular radio beacon at a given time. A pair of 30 reeds are provided for each beacon and several beacons are provided for in the apparatus.

Fig. 1 shows a radio receiver at 1 comprising a tunable circuit at 2 coupled to the antenna 3 and a switch at 4 to tune the circuit 2. A transformer 5 is arranged to pass the audio frequency output of the receiver to the electro-magnetic unit 6 shown in Fig. 5.

Fig. 2 illustrates a directional radio range beacon in which a pair of directional antennas 18 and 19 are arranged at an angle to one another for radiating waves modulated with particular frequencies such as 65 and 85 cycles respectively to facilitate explanation of the invention. The equisignal zones A, B, C, D, may be thought of as definite courses, ranges, or arbitrary lines of reference. However, since the functioning of the apparatus may appear complex in some particulars, an understanding of the mode of operation of the system will be aided by considering the movements of the illustrated vessels more particularly with respect to the approach toward, or proximity of the vessels, to the one or the other of the zones of maximum signal intensity, rather than to consider the movements of the

vessels with respect to the equisignal zones or arbitrary lines of reference. The apparatus herein described is not limited to operation on the equisignal zones, and these zones are here considered as of secondary importance. The description will be more readily understood if it is carried in mind that the course designator 66 associated with the panel 67, Fig. 5 is always in the position shown in the drawing when the zone of maximum 10 65 cycle signal intensity lies on the right-hand side of the vessel, and this holds good on any heading of the vessel whether steering toward or away from the beacon. The course designator 66 is changed over to its second position 15 only when the maximum 85 cycle signal zone lies on the right-hand side of the vessel when heading on a given course toward or away from the beacon.

Fig. 3 is a selective tuned reed or resonance relay constructed in accordance with my invention to eliminate the vibrating contacts common to such instruments and is comprised of a lever 22 pivotally fulcrumed at 23 to a supporting frame 24. A tuned reed 40, having an unbalanced air vane 37 fastened to its free end, is attached at its fixed end to one arm of the lever 22. The other arm of the lever 22 has attached thereto a spring 27 carrying a contact button 28. An adjustable contact 29 is arranged adjacent the button 28 to make a solid contact therewith when the reed 40 is in vibration and the aerodynamic force developed by the unbalanced air vane 37 causes the movably supported member 22 to move from its initial position or initial position of equilibrium as indicated by the dotted line 30, to its contact making position shown by the line 31. A tension spring 32 is arranged between the lever 22 and the frame 24 to assist in restoring the movable member 22 to its initial position against the stop-rest 33 in which position of the member 22 the contact between 28 and 29 is broken. Due to the bending of the spring 27 the button 28 exerts a rubbing motion on the face of the contact 29 thereby tending to keep the contact surfaces clean and of low resistance in the secondary circuit 34. One arm of the lever 22 constitutes the armature of the electromagnet 35 in the primary circuit 36.

Fig. 4 illustrates diagrammatically the dynamic forces developed by a reed 40 having differently shaped vanes fixed to its free end, and which forces are utilized in this invention. Differently shaped air vanes are shown at 37, 38 and 39. These vanes are fixed to the reeds 40 which form one side of the right-angled cantilevers 41, 41n, and 41o which are arranged to rotate around an axis of rotation 42. The arrows in the drawing show the direction in which the developed forces are effective when the reeds 40 are in a state of vibration. Considering first the vane 37, when a reed is in a state of vibration there is a centrifugal force developed which acts in the direction indicated by the arrow (a), or parallel to the length of the reed 40, or in other words, in a line parallel to the line of position of equilibrium, and this force (a) exerts a tension at the free end of the cantilever 41 to produce an effective and continuous torque around the axis 65 of rotation 42. The vane shown at 37 is a semi-spherical cup in common use on anemometers or wind speed indicators. When the reed 40 is in vibration and the vane 37 attached thereto is beating the air in two directions, the air offers 70 a greater resistance to the concave side k than

to the convex side of the cup thus producing an unbalanced force in the direction of the arrow b, or tangent to the curvilinear motion of translation of the vane around the axis of rotation 42. The resultant force of the two applied forces a and b, or the turning moment of the cantilever 41, is indicated by the arrow 31ab. At 38 is shown a balanced vane which beats against the same air resistance in both directions of its travel when the reed 40, to which it is attached, is in vibration. But owing to the fact that this vane 38 presents two working faces l and m, or inclined planes, to the resisting medium, an aerodynamic force is developed in the direction of the arrow d, or parallel to the length of the reed 40, and thus augments the centrifugal force c, the two forces tending to move the cantilever 41n in the direction 38cd. To utilize the three dynamic forces just explained I have combined the working faces of the vanes 37 and 38 in the improved vane shown at 39, 39p, q, and r, and taken in combination with the reeds 40 and the cantilever 41o, having an axis of rotation at 42, represents a novel feature of my invention. The vane 39 presents three working faces k, l, and m 25 to the resisting medium when the reed 40 is in vibration. The vane 39 is preferably hollow and closed on all sides and working faces except at k which is left open and produces the force (b) first considered in connection with the vane 37 30 and now identified by the arrows e and j in connection with vanes 39 and 39p. When the two faces l and m, 39, are alternately driven against the air by the reed 40, the vane 39 exerts a tension in the direction indicated at f, or parallel to the length of the reed, and k which causes a resistance to the movement of the reed 40 in only one direction of its travel, produces an unbalanced force in the direction e, or in one direction tangentially to the arc described by the free 40 end of the reed 40. It will thus be obvious that the forces developed by the vane 39 augmented by the centrifugal force (g) of the reed 40 which forms a side of the right-angled cantilever 41o, will produce an unbalanced turning moment or 45 torque in the direction 39efg. The vane 39p produces an unbalanced turning moment in the opposite direction indicated at 39hij. It will be understood that the principles of aerodynamics will be applied in the design of the air vanes, 50 and the surfaces of the vanes will be streamlined where low resistance is desired, and other advantages are to be gained thereby.

The vanes 39 and 39p, also shown in Fig. 5 are identical in construction in every particular 55 but one. Since all the vibrating reeds in my apparatus are tuned to different frequencies, the vanes must also be differently tuned as to size, shape, or weight to conform to the frequency at which they are designed to operate when attached to their respective reeds and thus develop resultant forces of the same magnitude as all the other reeds and vanes in the apparatus. The vane 39p develops a resultant force of the same magnitude as that developed by the vane 39 when the reeds 40 are vibrating with equal amplitude, but the resultants of the forces developed by the respective reeds and air vanes are effective in opposite directions as indicated at 39hij and 60 39efg. The cantilever 41o with two differently 65 tuned reeds 40 mounted thereon and extending in opposite directions, and having the air vanes 39 attached to said reeds, illustrates the method of operation of the instrument shown in Fig. 5. If the two reeds on the cantilever 41o are vi- 70 75

brating with equal amplitude, the forces developed by the reeds and their vanes are equal and opposite and the cantilever 410 cannot rotate on its axis 42. Should the vibratory amplitude of one reed increase while that of the opposite reed is decreased proportionately, the forces acting on the cantilever would become unbalanced and rotation would ensue in one direction or the other as indicated at 39_{effg} and 39_{hij}. At 39₁₀ and 39_q are two views of the new air vane, the shape of which is difficult to describe accurately. The embodiment of the invention illustrated in Fig. 5 comprises a pair of brackets 44 upon which the pivot spindle 42, supporting the cantilever movement 410, is pivotally mounted. Two levers 8-8 constructed in accordance with my invention are pivotally mounted at 9 on the right-angled cantilever movement 410. The levers 8-8 have a plurality of reeds 40 mounted on the short arms 13, all of said reeds having a different period of vibration. One pair of the reeds mounted on opposite sides of the movably supported member 410 are shown as having a tuned frequency of 85 cycles and 65 cycles respectively for purposes of explanation in this description. Each of the reeds 40 has an unbalanced air vane fixed at its free end as shown at 39, and each of said vanes is designed to function efficiently at the frequency to which its respective supporting reed is mechanically tuned. The combined structure shown by the reeds 40, the levers 8-8, the frame 410, and the pivot spindle 42, constitutes the balanced right-angled cantilever movement diagrammatically illustrated at 410, Fig. 4.

To the pivot spindle 42 is attached a spiral spring 45 for the purpose of maintaining and otherwise restoring the movement 410 to its normal position shown in the drawing when not actuated by unbalanced forces developed by the reeds 40 and their vanes 39. The pulsations which actuate the reeds 40 are transmitted from the electro-magnetic unit 6 to the long arms of the levers 8 by means of the armature rod 7, the pulsating currents energizing the unit 6 being derived from the receiver 1, Fig. 1, through the transformer 5. The pivot spindle 42 carries an arm 46 which carries a contact roller 47 which functions as a non-vibrating contact actuated by vibrating reeds, and constitutes one of the features of the invention described in connection with the structure shown in Fig. 3. Arranged under the roller 47 is shown a piece of insulating material 48 separating two metal contact strips 49 and 50 which are operatively arranged on a movable bar 51. The roller 47 normally rests on the insulation 48, but when the relay movement 410 is acted upon by unbalanced forces, the arm 46 causes the roller 47 to make contact with one or the other of the contact strips 49-50 in accordance with the relative intensities of the signals detected by the receiver 1, Fig. 1. The movable bar 51 forms a rack which is engaged by a pinion 52 which is operated by the thumbscrew 53, the thumbscrew 53 being provided for the purpose of adjusting the positions of the contact strips 49-50 under the contact roller 47. The relative positions of the contacts 49-50, under the contact roller 47, with respect to the operating positions of the movable member 410 and its contact making arm 46, are indicated on the dial 75. A dial pointer 54 is pivotally connected at 55 to the movable bar 51 for the purpose of indicating on the dial 75 the differential operating relation between the

movable contacts 49-50 and the other movable contact 47. The pointer 54 has a double body 56 provided with a slot 57 which is arranged to engage a movable fulcrum 58 which is held in position by the guide 59. The reason for employing a movable fulcrum 58 working in a slot 57 is to allow a reversal in the relative movements of the pointer 54 and the bar 51. When the fulcrum 58 is at the bottom of the slot 57 and below the pivot support 55 the pointer 54 will move 10 in the same direction as the bar 51. But when the fulcrum 58 is at the top of the slot 57 and above the pivot support 55, the pointer 54 will move in a direction opposite to that of the bar 51. This reversal in the relative movements of 15 the pointer 54 and the bar 51 is necessary under certain operating conditions of the apparatus. The movable fulcrum 58 is connected by a rack 60 with a gear 61, and which gear engages a rack 62 on connecting rod 63. The rod 63, which 20 is also operatively connected to the relay reversing switch 65, forms another rack 64 which is engaged by a manually operated gear and course designator 66. The panel 67 with which the dial pointer or course designator 66 is associated is designed to identify the various radio courses ranging around a particular beacon as illustrated in Fig. 2, and also determine and designate the proper setting necessary for operation of the instrument on a given course or equisignal zone. The proper setting of the course 25 designator 66 on the panel 67, for a given course which it is desired that a vessel should maintain, automatically adjusts the instrument to compensate for the ambiguous characteristics of the 30 transmitted signals of the double modulation type of directive radio beacon arranged for producing equisignal zones fixed in azimuth. The dial shown at 75 indicates the number of degrees or angular distance that a vessel is maintaining 35 a course to the right or left of a particular course or equisignal zone identified on the panel 67, taking also into account the fact that the vessel is proceeding to or from the beacon. The contact segments 49-50 are connected by 40 circuit wires 68 and 69 to the relay reversing switch 65 and then by circuit wires 71 and 72 to the primary relays on the relay panel 73 and from which panel the steering motor of the vessel is controlled through the circuit wires 74. 45 The wire 70 leading to the primary relays on the relay panel 73 is neutral to both circuits 68 and 69. The function of the reversing switch 65 is to reverse the order of actuation of the primary 50 relays on the panel 73 which are actuated through the circuits 68 and 69 by the closing of the contacts 49 or 50 by the contact roller 47. If now the gear 66 be turned clockwise in direction, the bar 63 will be moved to the right thus also operating the switch 65 and reversing the circuit 55 arrangement between contacts 49-50 and the two relays connected to wires 71-72. The relay panel 73 is a conventionally arranged panel in common use with a well known type of automatic pilot steering mechanism for ships and 60 which is controlled by the gyroscopic compass. The roller 47 in my apparatus takes the place of the repeater motor contact roller in the gyro-pilot system above mentioned and the contacts 49-50 in my apparatus take the place of the 65 contact rings in the gyro-pilot system, but since the gyro-pilot system is not a part of this invention, its mechanism has not been shown in the drawing beyond the relay panel connections 74.

The pair of reeds designated as having periods of 85 cycles and 65 cycles, respectively, are mounted in opposed operating relation in the differential relay Fig. 5, and are tuned to the modulation frequencies of a particular beacon in a system employing several of such beacons. When the audio frequency output of the receiver 1 energizes the electro-magnetic unit 6 through the transformer 5, the armature rod 7 actuates the levers 8, and the 85 cycle and 65 cycle reeds carrying the air vanes 39 are set in vibration. If a vessel equipped with this apparatus is proceeding toward the beacon on the equisignal zone or radio course A, as illustrated by the vessel 10, Fig. 2, and designated by the dial pointer 66 on the panel 67, the instrument will function in the following manner. If for example the vessel 10 remains exactly on the equisignal zone or course A, the 65 and 85 cycle reeds will vibrate with equal amplitudes and as heretofore explained, their tensions on the cantilever 40 will be of equal magnitude and in opposite directions, while the contact roller 47 will remain upon the insulation 48 and the relays on the relay panel 73 will not be actuated. If the vessel should move to the left of the designated course as illustrated at 11, Fig. 2, the vessel would be moving toward the side of the equisignal zone where the 85 cycle signal strength predominates and with the result that the 85 cycle reed will increase its vibratory amplitude, while the 65 cycle reed will proportionately decrease its amplitude, in consequence of which the roller 47 would be moved on to the contact segment 50. The circuit arrangement between the contacts 49-50 and the relays on the panel 73 is such, with the switch 65 in its present position, that when the roller 47 makes contact with the contact 50, the rudder of the vessel is automatically turned to the right or in a direction opposite to the movement of the roller 47. The rudder in this position will restore the vessel to its designated course on the equisignal zone, and when on the equisignal zone, the 85 and 65 cycle reeds will again be vibrating with equal amplitude and the retractile spring 45 will assist in restoring the roller 47 to its initial position on the insulation 48. If the vessel moves to the right of the course as illustrated at 12, the roller 47 will make contact with 49 due to the tension of the 65 cycle reed which increases its amplitude when the vessel moves to the right of the equisignal zone. With the circuit 69-70 closed, the rudder moves to the left or opposite to the movement of the roller contact 47 and the vessel is again restored to its designated course where the beacon signals are received with equal intensity, the reeds vibrate with equal amplitude, and the roller 47 is restored to its initial position on the insulation 48. It will thus be obvious that the selective differential control apparatus steers the vessel automatically by the directive radio beacon signals.

If it should be desired to maintain a course 10 degrees to the right of the equisignal zone C, and 65 while proceeding away from the beacon, as illustrated at 15, the thumbscrew 53, which is provided for the purpose of setting courses at different angular distances around the beacon, will be turned to the left or counterclockwise, thus moving the contact support 51 to the right thereby bringing the contact 50 under the roller 47, and the dial pointer or angular distance indicator 54 will have moved 10 degrees to the right, thereby indicating the course which will be automatically maintained. The course designator 66 is in the

correct position as shown in the drawing for this heading of the vessel since the maximum 65 cycle signal lies on the right-hand side of the vessel 15 when heading away from the beacon. If, for example, the vessel were made to steer an opposite course toward the beacon on course C, the 85 cycle maximum signal zone would then lie on the right-hand side of the vessel, and the course designator 66 would have to be changed over in order to designate "To beacon, Course C" on the panel 67 to permit proper functioning of the steering control apparatus. As heretofore explained, the contact roller 47 when resting on the contact 50 closes the circuit 68-70 and causes the rudder to be turned to the right. With proper adjustment of the apparatus the vessel will maintain a course 10 degrees to the right of the equisignal zone C. It will be understood that the degree of movement of the rudder is purposely limited, and the course will be automatically altered or corrected only a small amount at a time by means and methods well known and understood in the art. At 10 degrees to the right of the equisignal zone C the 65 cycle reed will have sufficiently increased its vibratory amplitude to move the roller 47 to the insulation 48 and in which position the rudder will be automatically restored to its neutral position by the relays on the relay panel 73. Any movement of the roller contact to the right or left will be met by the rudder moving in the opposite direction and restoring the vessel to its designated course.

If now, for example, the vessel at 16 is made to steer a course away from the beacon, on equisignal zone B, it will be found that the relative 35 positions of the differently characterized zones of maximum signal intensity are transposed with respect to the heading of the vessel, that is to say, where formerly the 65 cycle maximum signal lay on the right-hand side of the vessel, the 85 cycle 40 maximum signal now lies on the right-hand side of the vessel. This ambiguous relation of the transmitted signals with respect to the headings of a vessel on different beacon courses and in different directions on the courses, to or from the 45 beacon, has been provided for by means of the change-over mechanism shown at 66 which designates the proper setting of the instrument for steering a course to or from the beacon, by the reversing switch 65, and by the movable fulcrum 50 55 58 working in the slot 57 for reversing the relative movement of the pointer 54. This reversal of the order of actuation of the relays on the panel 73 by the circuit closing contacts 49, 50, and 47 can be carried out by other means such as would consist of a simple mechanical movement for reversing the position of the contacts 49 and 50 and eliminating the reversing switch 65, and it is to be understood that such modifications suggesting themselves to those skilled in 60 the art are within the scope of my invention.

Considering again the case in which the vessel 16 is heading away from the beacon on course B, if the course designator 66 is not changed over to indicate "From beacon, Course B", on the panel 67, the automatic steering apparatus will cause the vessel to execute a 180 degree turn from its course away from the beacon and will thereafter steer itself back toward the beacon as shown at 17. When the course designator 66 is moved to the right, the connecting rod 63 operates the reversing switch 65 and also the gear 61 which moves the fulcrum 58 to the top the slot 57 in the body of the dial pointer 54. This change in the position of the fulcrum 58 in the slot 57 reverses 70 75

the movement of the pointer 54 relative to the movement of the rack 51.

It will be apparent that this embodiment of the invention requires no technical knowledge on the part of the navigator for an intelligent use of the same in practice. The relative positions of the principal radio courses are known to the navigator and the ambiguous relation of the transmitted signals on the various courses is provided for in the apparatus.

It is to be understood that the invention is not limited to any specific construction but might be embodied in various forms without departing from the spirit of the invention or the scope of the appended claims.

Having described my invention what I now claim is:

1. In a navigational apparatus adapted for cooperation with a source of differently characterized signals to delimit definite courses, the combination including a receiving device, a selective differential relay connected to said receiving device and arranged to respond to the relative magnitudes of said signals, a contact maker associated with said relay, a set of adjustable contacts arranged adjacent said contact maker, means to adjust the operating relation between said adjustable contacts and said contact maker, and automatic steering apparatus control circuits arranged with said contacts for differential actuation thereby.

2. In apparatus according to claim 1, in which an indicating means is operatively arranged to indicate the degree of adjustment of the adjustable contacts relative to the position of the contact maker.

3. In apparatus according to claim 1, in which a course designator is operatively arranged with the steering apparatus control circuits for designating and determining the proper operating adjustment of the relay control apparatus for operation on a given course.

4. In apparatus according to claim 1, in which a course designator; a means for indicating the degree of adjustment of the adjustable contacts, together with means for reversing the order of movement of said indicating means; and means for reversing the order of control of the steering apparatus control circuits, are operatively associated for simultaneous adjustment of the relay control apparatus for operation on a given course.

5. In navigational apparatus adapted for use with a source of differently characterized signals producing equisignal zones fixed in azimuth, the combination comprising automatic steering control apparatus simultaneously and differentially responsive to said signals and operatively arranged with steering mechanism on a movable body for causing the latter to maintain a predetermined course relative to a given equisignal zone, course setting means to make said steering control apparatus respond to predetermined relative magnitudes of said signals to cause said movable body to maintain a predetermined course at a predetermined angular distance to the right or left of said equisignal zone, and means to indicate and determine the angular distance of a given course to the right or left of said equisignal zone.

6. In apparatus as defined in claim 5, in which means is associated with the steering control apparatus to identify the various equisignal zones and designate the proper adjustment of said control apparatus for maintaining a given course on a given equisignal zone in a given direction rela-

tive to the direction of the source of signals producing said zones.

7. In apparatus as defined in claim 5, in which reversing means for the angular distance indicating means; means for reversing the order of the operating control of the steering control apparatus; and designating means, are operatively associated with the steering control apparatus.

8. In automatic steering control apparatus, a receiver of differently characterized simultaneous signals, an electro-mechanical resonance differential control device operable responsive to the frequencies and relative magnitudes of said signals, and automatic steering apparatus control circuits operatively associated with said control device for differential actuation thereby.

9. A mechanically selective differential device operative in response to the relative magnitudes of a plurality of simultaneously applied actuating forces, consisting of a movably supported member, a plurality of vibratile elements arranged in opposed operating relation with said member for causing the latter to move differentially, means for causing said elements to vibrate, and apparatus operatively associated with said member for actuation thereby.

10. A selective differential control device comprising a movably supported member, a plurality of differently tuned vibratile elements arranged in opposed operating relation with said member and adapted for developing centrifugal forces which actuate said member, means to cause said elements to vibrate, and desired apparatus operatively associated with said member for actuation thereby.

11. The combination comprising a movably supported member, a plurality of vibratile elements arranged in opposed relation integrally with said member to cause the latter to move differentially when the opposed actuating forces developed by said elements are unbalanced, means to cause said elements to vibrate, and work circuits operatively associated with said member for differential actuation thereby.

12. The combination comprising a movably supported member, a plurality of differently tuned vibratile elements provided with unbalanced vanes operatively arranged in opposed relation with said member to effect a resultant differential movement thereof, means to cause said elements to vibrate, and apparatus associated with said member for actuation thereby.

13. A selective differential control device comprising a movably supported member, a plurality of differently tuned reeds mounted in opposed operating relation on said member, an unbalanced air vane formed at the free end of each of said reeds to develop aerodynamic actuating forces the relative magnitudes of which are proportional to the relative vibratory amplitudes of said reeds respectively, means to cause said reeds to vibrate in resonance with received signals having frequencies corresponding to the frequency of vibration of said reeds, contact making means associated with said member and arranged to make contact differentially with a plurality of contacts adjacent said contact making means, a plurality of work circuits connected to said contacts and said contact making means, and apparatus connected to said work circuits.

14. A differential device which responds to the difference in magnitude of a plurality of simultaneously received signals, comprising a plurality of vibratile elements for producing dynamic forces acting in opposition on a balanced rotary

- movement, means to actuate said elements selectively, circuit actuating means co-operating with said rotary movement for actuating a set of control circuits, and apparatus connected to said control circuits to be actuated thereby.
15. In combination, a craft equipped with suitable automatic steering apparatus, control means mechanically selective and differentially responsive to a plurality of received signals and operatively associated with said steering apparatus, and course setting means associated with said responsive control means for the purpose of regulating the function of said control means whereby the steering apparatus is made to respond to desired differences in strength of said received signals to cause said craft to automatically maintain selected courses ranging in different desired directions.
16. In automatic steering apparatus for a movable body, comprising means for receiving and detecting radio signals, control means mechanically selective and differentially responsive to the distinctive modulation components of said signals, course indicating means associated with said control means, and steering mechanism for said body controlled by said control means.
17. Steering apparatus for a movable body, comprising a radio receiver for supplying two simultaneous currents of different frequencies and
- having relative magnitudes which vary in accordance with the course of the body, a mechanical resonance differential control device responsive to the frequencies and magnitudes of said currents, and steering mechanisms for said body controlled by said control device.
18. A selective relay, comprising a movably supported member, vibratile aerodynamic means arranged with said member for causing the latter to move, means for causing said vibratile means to vibrate, and apparatus operatively associated with said member for actuation thereby.
19. A selective relay, comprising a movably supported member, a tuned vibratile element having an unbalanced vane operatively arranged with said member for causing the latter to move, primary means for causing said element and vane to vibrate, and secondary means associated with said member for actuation thereby.
20. The combination including a plurality of vibratile elements for producing dynamic forces acting in opposition on a movable member, means for actuating said elements selectively, means co-operating with said movable member for differentially actuating a plurality of control circuits, and means for altering and indicating the relative operating adjustment between said movable member and said control circuits.

THEOPHILE E. BROCKSTEDT.
